UNITED STATES PATENT OFFICE.

IRVING LEWIN, OF NEW YORK, N. Y., ASSIGNOR TO STAR RIBBON MANUFACTURING CO., OF NEW YORK, N. Y., A CORPORATION OF NEW YORK.

NECKTIE.

1,186,321.

Specification of Letters Patent.

Patented June 6, 1916.

Application filed July 24, 1916. Serial No. 41,720.

To all whom it may concern:

Be it known that I, IRVING LEWIN, a citizen of the United States, and a resident of the city of New York, borough of Manhattan, in the county and State of New York, have invented a new and Improved Necktie, of which the following is a full, clear, and exact description.

The invention relates to woven neckties, and its object is to provide a new and improved necktie which is highly ornamental and reinforced at the front.

In order to accomplish the desired result use is made of a flat tubular body and an ornamental reinforcing strip overlying the front of the said body and having its side edges integral with the said body front.

A practical embodiment of the invention is represented in the accompanying drawings forming a part of this specification, in which similar characters of reference indicate corresponding parts in all the views.

Figure 1 is a face view of the necktie; Fig. 2 is an enlarged cross section of the same on the line 2—2 of Fig. 1; and Fig. 3 is a face view of a modified form of the necktie.

The body A of the necktie is woven in tubular form, and on the front of the body is arranged an ornamental strip B having its sides turned under and its edges interwoven with the front of the body A. The strip B extends preferably throughout the length of the body A and its sides are spaced from the sides of the body A thus providing a raised ornamental strip in the form of a box-plait on the front of the body A and one which incidentally reinforces the body A. It is understood that the body A is narrowed throughout a portion between the ends, as plainly indicated in Fig. 1, while the ornamental reinforcing strip B is preferably of the same width throughout its length. As shown in Fig. 3, the strip B

is in two parts spaced apart at the neckband or collar portion to allow easy slipping or shifting of the necktie when used on turndown collars.

In manufacturing the necktie, the body A and the strip B are simultaneously woven. Both the strip B and the body A may be ornamented by the use of differently colored yarns and woven according to predetermined designs.

Having thus described my invention, I claim as new and desire to secure by Letters Patent:

1. As an article of manufacture, a necktie having a flat tubular body and an ornamental longitudinally extending reinforcing strip of less width than the body and overlying the front of the said body at the center thereof, said strip having its side edges integral with the said body front.

2. As an article of manufacture, a necktie having a flat tubular woven body and a woven longitudinally extending strip of less width than the body and overlying the front of the said body at the center thereof, the sides of the said strip being turned under and interwoven along the edges with the said body front.

3. As an article of manufacture, a necktie having a flat tubular woven body, and a woven strip overlying the front of the said body throughout the length thereof and with its sides spaced from the sides of the body, the sides of the said strip being turned under and interwoven along the edges with the said body front at each side of the center thereof.

In testimony whereof I have signed my name to this specification in the presence of two subscribing witnesses.

IRVING LEWIN.
